UNITED STATES PATENT OFFICE.

BENJAMIN BAKEWELL, JR., OF PITTSBURG, PENNSYLVANIA.

DESIGN FOR BEER-MUGS.

Specification forming part of Design No. **7,342**, dated March 31, 1874; application filed March 16, 1874.
[Term of Patent 7 years.]

To all whom it may concern:

Be it known that I, BENJAMIN BAKEWELL, Jr., of Pittsburgh, in the county of Allegheny and State of Pennsylvania, have invented a new and useful Design for Beer-Mugs; and I do hereby declare the following to be a full, clear, and exact description thereof, reference being had to the annexed drawing forming a part of this specification, which is a view of my improved design for glass beer-mugs.

My design consists in forming a mug in the representation of a barrel, having staves *a* and hoops *b*, and preserving the general form

or outline of a barrel. This mug is fitted with a handle, as usual.

What I claim as my invention, and desire to secure by Letters Patent, is—

A glass beer-mug in representation of a barrel, having staves and hoops, as described.

In testimony whereof I, the said BENJAMIN BAKEWELL, Jr., have hereunto set my hand.
